Boiros et al., U.S. Appl. No. 29/579,305, filed Sep. 29, 2016 for Bottle.

Primary Examiner — Anhdao Doan*Assistant Examiner* — Mary S Malley(74) *Attorney, Agent, or Firm* — Nixon & Vanderhye P.C.(57) **CLAIM**

The ornamental design for a bottle, as shown and described.

DESCRIPTION

FIG. 1 is a perspective view showing an embodiment of our new ornamental design;

FIG. 2 is a front view thereof;

FIG. 3 is a side view thereof;

FIG. 4 is a cross section taken along line 4-4 of FIG. 2; and, FIG. 5 is a cross section taken along line 5-5 of FIG. 2.

The drawing disclosure does not depict the bottom view because this view forms no part of the claimed design.

The broken lines represent environmental structure or unclaimed portions of the bottle and do not form a portion of the claimed design.

While the bottle is transparent, the “see-through” details are not shown for the sake of clarity.
